FIG. 1

FIG. 2

FIG. 3

FIG. 4

FIGURE 1 is a top plan view of the gameboard showing my new design.

FIGURE 2 is a side elevational view of the gameboard, the other side being substantially identical to the side shown in FIGURE 2.

FIGURE 3 is an end elevational view taken from the left as shown in FIGURE 1.

FIGURE 4 is an end elevational view taken from the right as shown in FIGURE 1.

The essential feature of my design resides in the full line portion of the drawing.

I claim:

The ornamental design for a gameboard, substantially as shown and described.
